INTERLOCK FOR ELEVATOR DOORS

Arthur Ennis Prince, Chatham, N. J., assignor to
 Otis Elevator Company, New York, N. Y., a
 corporation of New Jersey

Application March 18, 1942, Serial No. 435,124

13 Claims. (Cl. 187—61)

The invention relates to interlocks for elevator hatchway doors.

In elevator installations in which the operation of the elevator car is controlled by the passengers and intending passengers themselves and in which the hatchway doors are manually operated, it is customary to provide each door with a lock and to provide a retiring cam on the car which acts, when a stop is made at a floor, to unlock the door at that floor. Contacts are associated with the lock to prevent operation of the car unless the door is closed and locked. Also contacts are usually provided to prevent energization of the retiring cam unless the door is closed. The invention is especially directed to interlocks of this character.

The object of the invention is to provide an interlock which is reliable in operation and which is of simple yet fool-proof construction.

The invention involves the construction of an interlock in which all access to the circuit controlling elements is eliminated and in which any unwarranted manipulation of the interlock is obviated. The invention also involves a latch for latching the door in closed position, a magnet carried by the door for controlling the operation of the latch, and locking means for locking the latch in latched position, thereby locking the door.

In carrying out the invention according to the arrangements which will be described, the latch is mounted in an interlock housing in position to enter a recess in the edge of the door when the door is closed. An opening is provided in the housing for the latch, this opening being closed by the latch. The magnet for controlling the latch is a permanent magnet and is carried inside the door. When the door is closed, the magnet acts in conjunction with an armature carried by the latch to move the latch to latched position. A lock member in the housing is moved into position to lock the latch in latched position when the car is to be operated, thus locking the door in closed position. Contacts are operated by the latch to prepare the circuit for the retiring cam for operating the locking member. Also contacts are operated by the locking member which act to prevent operation of the car unless the door is closed and locked. All these contacts are within the interlock housing and as the housing is entirely enclosed, the opening in the housing for the latch being closed by the latch, the contacts are inaccessible. When the car is stopped at the floor, the locking member is moved to unlocking position by the retiring cam.

5 The latch is formed so that, when it is freed by the locking member, it forces itself out of the recess in the door against the force of the permanent magnet upon the door being moved toward open position.

A general idea of the invention, the mode of carrying it out which is at present preferred, and various features and advantages thereof will be gained from the above statements. Other features and advantages of the invention will be apparent from the following description and appended claims.

In the drawings:

15 Figure 1 is a schematic representation of interlocking mechanism embodying the invention applied to a swing type hatchway door;

Figure 2 is a view in elevation of the interlock with parts broken away;

Figure 3 is a view in section taken along the line 3—3 of Figure 2;

Figure 4 is a view in section taken along the line 4—4 of Figure 2;

Figure 5 is a view in section taken along the line 5—5 of Figure 2;

20 Figure 6 is a fragmental detail of the portion of the mechanism of Figure 2, illustrating the interlock in unlatched condition;

Figure 7 is a fragmental detail taken along the line 7—7 of Figure 6;

Figure 8 is a fragmental detail taken along the line 8—8 of Figure 2;

Figure 9 is a view similar to Figure 2 of interlocking mechanism embodying the invention applied to a sliding type hatchway door; and

Figure 10 is a view similar to Figure 6, illustrating the interlock of Figure 9 in unlatched condition.

Referring first to Figure 1, the elevator car 10 is illustrated as stopped at a floor. The hatchway door at that floor is designated 11. The door is a swing door and is supported by hinges 12 and 13 secured to the door casing 14. The casing is embedded in the hatchway wall and rests on a sill plate 15 in the floor 16. The lower hinge 13 is connected to a door check and closer in a box 17 embedded in the floor. The door is illustrated as of hollow metal construction. It is provided with a fixed knob 18 for pulling it open from the outside when the door is unlocked.

The interlock is positioned near the top of the door. A non-magnetic plate 20, secured to the edge of the door, is provided with a recess 21 to receive the latch, thereby forming a keeper. The latch comprises a pivoted arm 23 having a hooked end 22 for extending into the recess,

This arm is pivotally mounted in a housing 24 embedded in the door casing, at least the face of the housing being of non-magnetic material. The hooked end of the arm extends through an opening 29 in the face of the housing. The arm carries an armature 25 adapted to be attracted by a permanent magnet 26 mounted on plate 20. This magnet acts to pull the latch into the latching position illustrated when the door is closed. The latch is locked in this position by a locking member 27 secured to a shaft 28 pivotally mounted in the housing. This shaft extends outside the housing where it is provided with an operating arm 30 having a roller 31 on the outer end. The locking member is biased to locking position 15 by arm 30 and a spring 32 between a wall of the housing and the lug 33 depending from the locking member.

The locking member 27 is moved to unlocking position by a retiring cam 34 mounted on the 20 elevator car. This cam is retracted electromagnetically as by an electromagnet 37 mounted on the car sling 39. A chain 35, passing over an idler pulley 38, connects the cam to the armature 36 of the electromagnet. The energization of the electromagnet is controlled by contacts 40 in the housing operated by the latch. These contacts are usually termed auxiliary door contacts. When the door is closed and latched, these contacts engage to permit the energization of the electromagnet to retire the cam. The retiring of the cam frees arm 30 permitting the locking member to move into position behind the latch to lock the door. The locking member when in this position engages contacts 41 to permit the operation of the car. These contacts which are also in the housing are usually termed door lock contacts. When the car makes a stop at the floor, the retiring cam magnet is deenergized, permitting the extension of the retiring cam. The retiring cam moves the operating arm counter-clockwise, thereby moving the locking member into unlocking position. This opens the door lock contacts and frees the latch arm. The hooked end of the arm is bevelled as will be seen from later description so that as the door is pulled on from the outside or pushed against from the inside the latch is forced out of the recess 21 against the force of magnet 26. This opens the auxiliary door contacts and permits the full opening of the door. The latch is biased by its own weight to unlatching position so that as the door moves away from the interlock housing the latch remains in unlatching position where it cooperates with the locking member to retain the locking member in the position to which it was moved by the retiring cam.

Details of construction of the interlocking mechanism are shown in Figures 2 to 8 inclusive to which reference may now be had. The non-magnetic plate 20 is secured to the edge 45 of the door by screws 46, an opening 47 being provided in the edge of the door to accommodate the plate. The permanent magnet 26 is secured to plate 20 by a strap 48. Threaded studs 50 extend inwardly from the plate, the strap being clamped to these studs by nuts 51. The magnet is of the horse shoe type preferably one of high coercion force and high retentivity. A depression 52, formed in plate 20 to receive the ends of the magnet, reduces the distance between the magnet and the armature of the latch.

The latch arm 23 is pivotally mounted on a pin 54 positioned in a boss 55 formed in the interlock housing 24. This housing comprises a frame 56,

5 of non-magnetic material enclosed on the sides by side plates 57. The side plates are secured to the frame by screws 58. An opening 60 is provided in the door casing to receive the housing, the housing being secured to the casing by screws 61 extending through the ends of the face 62 of the housing. An opening 59 is provided in the back of the door casing to provide access to the side plate on that side of the housing enabling this side plate to be removed to gain access to the inside of the housing. A stop 49 is formed on the door casing for stopping the door as it moves to closed position.

The opening 29 in the face of the housing and the recess 21 in plate 20 for the hooked end 22 of the latch arm are directly opposite each other, the recess 21 being slightly longer than the opening 29 to take care of any misalignment. The latch arm is formed by two side members 63 from between which the hooked end 22 extends at the upper end of the latch. These side members straddle the boss 55 and are provided with apertures into which the pin 54 extends to form the pivot for the latch. The side members are joined in the front opposite magnet 26 by a web 64 to form a support for the armature 25. The armature is secured to the latch by screws 65. A recess 66, formed in the rear surface of face 62 to receive the armature, decreases the distance between the armature and the magnet 26. The side members are also joined in the back by another web 67 for cooperating with the locking member 27 to lock the door in closed position.

The locking member 27 is secured to shaft 28 35 as by a set screw 68. The shaft 28 is pivotally mounted in boss 70 formed on the back of the housing. The end of the locking member adjacent the web 67 is cut away to form a rectangular key 71. A rectangular slot 72 slightly larger 40 than key 71 is formed in web 67 to permit the latch to fall back over the key when the door is unlatched, as illustrated in Figure 6. When the latch is released it is brought to a stop by the engagement of the web with the shoulders 73 formed on the locking member at the base of key 71. When the door is closed and the latch is in latching position the door is locked by rotational movement of the locking member by its operating arm 30 into position placing the key 71 45 at an angle with respect to slot 72 as shown in Figure 4 which prevents movement of the latch out of latching position. The operating arm 30 is secured to shaft 28 outside the casing by a set screw 75. A spacing washer 76 is pinned to shaft 28 between the operating arm and the back of the housing. The operating roller 31 for arm 30 is mounted on a pin 77 secured to the outer end of the arm. Biasing spring 32 for the locking member extends between the lug 33 depending from the locking member and the opposite side plate 57, being positioned by spring seats 78 and 79 on the lug and side plate respectively.

60 The door lock contacts operated by the locking member 27 comprises a pair of stationary contacts 80 and 81 mounted on an insulating block 82. This block is secured to the back wall of the housing as by screws 83. Screws 84 secure the contacts to the block and also serve for connecting the contacts in the system, the insulating block being recessed to provide space for these connections to be made. To facilitate this construction the stationary contacts are bent back as indicated in Figure 5. The stationary contacts are bridged by contact springs 86 having contact tips 87 for engaging the lower legs of

the stationary contacts. These springs are mounted on an insulating block 88 secured as by screws 90 to an extension 91 from the locking member 27. Bridging piece 92 is connected across the lower ends of the spring contacts, these parts being secured to the insulating block in an assembled relation by screws 93. The contact springs rest in troughs 94 in insulating block 88, the angles of these troughs being such that the contact springs are swung away from the bottoms of the troughs to provide good contact engagement when the door is locked and are picked up by the bottoms of the troughs to disengage the contact points thereon from the stationary contacts before the key 71 becomes parallel with slot 72 to unlock the door.

The auxiliary door contacts comprise a pair of stationary contacts 95 and 96 mounted on an insulating block 97. To facilitate obtaining access to these contacts, the block is arranged on a dovetail slide 98 secured to the top of the housing as by screws 99. Terminal screws 100 secure these contacts to the block and also serve for connecting the contacts in the system. The stationary contacts are bridged by contact springs 101 having contact tips 102. These springs are mounted on an insulating block 103 secured as by a screw 104 to latch arm 23. The insulating block is positioned by a shoulder 105 formed thereon which engages the upper end of the web 67. A bridging piece 106 is connected across the lower ends of the spring contacts, these parts being secured to the insulating block in assembled relation by screws 107. The contact springs rest in troughs 108 in insulating block 103, the angles of these troughs being such that the contact springs are swung away from the bottoms of the troughs to provide good contact engagement when the door is latched in closed position and are picked up by the bottoms of the troughs to disengage the contact points thereon from the stationary contacts before the hooked end of the latch moves out of the recess 21 in plate 20 to unlatch the door. An opening 113 is provided in the top of the housing for the connecting wires, a conduit connector 114 being illustrated as secured to the housing in this opening.

The extreme end 110 of the hooked end 22 of the latch arm is bevelled back as indicated in Figure 3. The purpose of this arrangement is so that the edge 111 of the recess 21 in plate 20, by engaging this bevelled portion as the door is moved toward open position under conditions where the latch is not locked, forces the latch inwardly of the interlock housing against the force of magnet 26 to unlatch the door. The opening 29 in the front plate of the housing is provided with a flange 112 which extends inwardly of the housing along the side opposite bevelled edge 110 and top and bottom of the opening to prevent access to the inside of the housing around the bevelled portion 110 of the latch, when the latch is released and the door is open. This entirely eliminates access to the circuit controlling mechanism of the interlock from the outside.

Although when the door is unlatched and open the hooked end of the latch is flush with or back of the face of the interlock housing which renders it extremely difficult for anyone manually to pull the latch into latching position, it may be desirable to provide mechanism to positively retain the latch in unlatched condition. An arrangement for effecting this operation has been illustrated. This comprises member 115 of magnetic material pivotally mounted on a pin 116

extending into a lug 117 formed on the rear surface of the face of the housing. This pivot is near the bottom of the member so that the member is biased by its own weight, augmented by a spring if desired, for clockwise movement about its pivot as indicated in Figure 2. In the bottom of this member on the opposite side thereof is a notch 118, for cooperating with a pin 120 extending from the side of the latch arm 23 to retain the latch in its unlatched position. When the door is closed the member 115 is in the position illustrated in Figure 2. As the door is opened and the latch moves clockwise about its pivot into unlatched position pin 120 moves beneath the notch 118 and the member falls clockwise into position with the notch over the pin as illustrated in Figure 6 to hold the latch in unlatched position. Thus unwarranted manipulation of the interlock is entirely obviated.

In operation, assume that the door is closed and latched as indicated in Figure 2 and that the retiring cam has been extended to operate arm 30 to position key 71 parallel with slot 72 in the latch 23 as indicated in Figure 7. As the door is moved to open position the edge 111 of recess 21 pushing on the bevelled portion 110 of the latch, forces the latch clockwise about its pivot into unlatched position against the force of magnet 26. During this movement contact springs 101 disengage stationary contacts 95 and 96 to open the auxiliary door contacts before the hooked end of the latch arm is moved out of recess 21, thereby assuring that the auxiliary door contacts are open when the door is unlatched. As the door moves outwardly the magnet reaches a position where it is no longer able to move the latch toward latching position so that the latch falls all the way out with the web 67 resting against shoulder 73 of locking member 27. Also, with further movement of the door the magnet releases member 115 which drops into position with the notch 118 over pin 120. This holds the latch in unlatched position while the door is open.

Upon closure of the door, as it nears the fully closed position it reaches a point where the magnet pulls member 115 counterclockwise about its pivot releasing the latch so that as the door moves to fully closed position the latch is pulled counterclockwise about its pivot by the magnet into latching position. After the hooked end of the latch has moved into recess 21 and just before the latch reaches its final position the contact springs of the auxiliary door contacts bridge the stationary contacts preparing the circuit for the retiring cam magnet.

Upon a button being pressed to call the car, the retiring cam magnet is energized retracting the cam and permitting locking member 27 to be rotated into locking position with the key 71 at an angle to slot 72. After the latch becomes locked and just before the locking member reaches its final locking position, contact springs 86 bridge stationary contacts 80 and 81 to permit the operation of the car. As the car comes to a stop at the floor for which the push button was pressed, the retiring cam magnet is deenergized extending the cam to cause the opening of the door lock contacts and thereafter the unlocking of the latch of the interlock for the hatchway door at that floor, permitting the opening of the door as above described.

It is to be noted that as the key 71 is in the slot 72 when the door is open, should the retiring cam magnet accidentally become energized as for example as the result of a ground in the

circuit for the retiring cam magnet, the slot prevents rotative movement of the locking member 27 to close the door lock contacts after the cam has been retired, thereby preventing operation of the car.

The invention is also applicable to sliding doors and an arrangement for sliding doors is illustrated in Figures 9 and 10. The door 130 is of hollow metal construction and has a non-magnetic plate 131 secured thereto in the opening 133 in the edge of the door. A permanent magnet 134 is secured to the back of the plate by a strap 135 as before. A recess 136 is provided in the plate to receive the latch, thereby forming a keeper. The latch comprises a catch member 137 pivotally mounted on a pin 138 supported by lugs 139 in the interlock housing. This catch extends through an opening 140 in the face of the housing and is provided with a hooked end 141 for extending into recess 136 in plate 131. Portions 142 and 143 of the catch are circular, being of a radius swung from the center of pivot pin 138 such as to completely cut off the opening 140.

The arm 144 of the latch is separate from the catch and is cut away in back of the catch as as 145, this cut away portion engaging the back of the catch to hold the catch in latching position as illustrated in Figure 9. The hooked end of the catch has a bevelled portion 146 which is engaged by the top edge 147 of recess 136 when the door is pulled open to force the latch counterclockwise about its pivot into position releasing the latch and permitting full opening of the door. During this unlatching operation, the lower end 148 of the catch pushes the latch arm 144 clockwise about its pivot against the force of magnet 134 so that as the door moves into open position the latch arm falls into position with the web 150 against the shoulder 13 formed on the locking member 27, as illustrated in Figure 10.

It is preferred that the catch be biased to unlatching position about its pivot and a stop 151 is formed on the latch to engage the rear surface of the face of the housing to limit the movement of the catch in the unlatching operation. However, if desired an additional bevelled surface 152 may be provided on the hooked end of the catch as illustrated to be engaged by the edge 147 of the recess to force the catch into unlatching position upon closing of the door in case the catch happens to be out of unlatched position at this time. As the door reaches closed position armature 153 on latch arm 144 is pulled to attracted position and the latch arm forces the catch clockwise about its pivot into latching position. A stop 154 is formed on the catch to engage the rear surface of the face of the housing to limit the clockwise movement of the catch. As before, upon the cam being retired the locking member 27 acts to lock the latch arm into locking position thereby locking the door. It is to be noted that when the door is unlatched any movement of the catch will have no effect on the latch arm which remains in unlatched position.

It is seen therefore that the interlocking mechanism satisfies all the requirements of a positive interlock and is of fool-proof construction. Access to all circuit controlling elements being entirely eliminated, there is no possibility of any one becoming shocked by touching any of the contacts. In the case of the swing door, the latch is positively held in unlatched position so

that manual release of the latch is prevented. In the case of the sliding door, manipulation of the catch can not release the latch. The magnet acts to hold the door in closed position thereby minimizing rebound. The operating magnet being on the door prevents the unauthorized operation of the interlock by a magnetizable plate. An authorized service man to do work on the installation which necessitates operation of the car with the door open must therefore carry with him a magnet of at least a certain strength for operating the interlock. The operating magnet being a permanent magnet eliminates wires being run into the door. The arrangement described is particularly suitable for flush type hatchway doors as the interlock housing may be mounted inside the door casing as illustrated with the magnet 26 inside the door, the operating arm and roller being well to one side of the cam 10 (see Figure 3).

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. Interlock mechanism for an elevator hatchway door comprising; a non-magnetic plate secured to the edge of the door and having a recess therein, a housing secured to the door casing, a latch pivotally mounted in said housing and having a hook for entering said recess; a permanent magnet inside the door and mounted on said plate; an armature carried by said latch in position to be attracted by said magnet as the door is closed to pull the latch into position to move the hook into latching position in said recess and thus latch the door in closed position, and a locking member mounted in said housing biased to lock said latch in latching position.

2. Interlock mechanism for an elevator hatchway door comprising; a non-magnetic plate secured to the edge of the door and covering an opening in the edge of the door; said plate having a recess therein; a housing opposite said plate and extending into the door casing through an opening therein, said housing having a non-magnetic face with an opening therein opposite said recess and being secured to the door casing; a latch having an arm pivotally mounted in said housing and a hook for entering said recess from said opening in said housing face; a permanent magnet inside the door mounted on the rear of said plate; an armature carried by said latch arm in position to be attracted by said magnet as the door is closed to pull the latch into position to move the hook into latching position in said recess and thus latch the door in closed position; and a member pivotally mounted in said housing for locking said latch arm in latching position, said member being biased to locking position.

3. Interlock mechanism for an elevator hatchway door comprising; a movable latch attached to the door casing, a keeper on the door for the latch; and a magnet carried by the door for pulling the latch into position to engage the keeper as the door is closed to latch the door, said latch having a surface for cooperating with an edge of the keeper to force the latch into unlatched position against the force of said magnet as the door is opened.

4. Interlock mechanism for an elevator hatch-

way door comprising; means forming a recess in the edge of the door; a latch pivotally mounted in the door casing and having a hook for entering said recess; a permanent magnet carried by the door for pulling the latch into position to move said hook into latching position in said recess as the door is closed to latch the door; and a locking member for locking said latch in latching position, said latch having a surface for cooperating with an edge of said recess when said locking member is released to force the latch into unlatched position against the force of said magnet as the door is opened.

5. Interlock mechanism for an elevator hatchway door comprising; a non-magnetic plate secured to the edge of the door and covering an opening in the edge of the door, said plate having a recess therein; a housing opposite said plate and extending into the door casing through an opening therein, said housing having a non-magnetic face with an opening therein opposite said recess and being secured to the door casing; a latch having an arm pivotally mounted in said housing and a hook for entering said recess from said opening in said housing face; a permanent magnet inside the door mounted on the rear of said plate; an armature carried by said latch arm in position to be attracted by said magnet as the door is closed to pull the latch into position to move the hook into said recess and latch the door in closed position; and a member pivotally mounted in said housing for locking said latch arm in latching position, said member being biased to locking position, said hook having a bevelled surface for cooperating with an edge of said recess upon the door being pulled open when said locking member is released to force said hook into unlatching position against the force of said magnet to unlatch the door.

6. Interlock mechanism for an elevator hatchway door comprising; a non-magnetic plate secured to the edge of the door and covering an opening in the edge of the door, said plate having a recess therein; a housing opposite said plate and extending into the door casing through an opening therein, said housing having a non-magnetic face with an opening therein opposite said recess and being secured to the door casing; a latch having an arm pivotally mounted in said housing and a hook for entering said recess from said opening in said housing face, said hook shutting off access to said housing through said opening in the housing face; a permanent magnet inside the door mounted on the rear of said plate; an armature carried by said latch arm in position to be attracted by said magnet as the door is closed to pull the latch into position to move the hook into said recess and latch the door in closed position; a locking member pivotally mounted in said housing in back of said latch arm and having a key for engaging the back of said latch arm to lock the latch in latching position, said locking member being biased to locking position, said back of said latch arm having a recess opposite said key; an operating arm for said locking member outside the housing; and a retiring cam carried by the car for operating said operating arm to move said locking member into position with said key in position with respect to said recess in said latch arm to free the latch arm for backward movement, thereby unlocking said latch, said hook having a bevelled surface for cooperating with an edge of said recess in said plate upon the door being pulled open when said locking member is in unlocking position to force said latch

backward into unlatching position against the force of said magnet to unlatch the door.

7. Interlock mechanism for an elevator hatchway swing door comprising; a non-magnetic plate secured to the edge of the door and covering an opening in the edge of the door, said plate having a recess therein; a housing opposite said plate and extending into the door casing through an opening therein, said housing having a non-magnetic face with an opening therein opposite said recess and being secured to the door casing; a latch having an arm pivotally mounted in said housing and a hooked end on said arm for entering said recess from said opening in said housing face; a permanent magnet inside the door mounted on the rear of said plate; an armature carried by said latch arm in position to be attracted by said magnet as the door is closed to pull the latch arm into position to move its hooked end into said recess and thus latch the door in closed position; a locking member pivotally mounted in said housing in back of said latch arm and having a key for engaging the back of said latch arm to lock the latch in latching position, said locking member being biased to locking position, said back of said latch arm having a recess opposite said key; an operating arm for said locking member outside the housing; a retiring cam carried by the car for operating said operating arm to move said locking member into position with said key in position with respect to said recess in said latch arm to free the latch arm for backward movement, thereby unlocking said latch, the outer end of said hooked end being bevelled on its surface toward the hatchway for cooperating with the adjacent edge of said recess in said plate upon the door being moved toward open position when said locking member is in unlocking position to force said latch backward into unlatching position against the force of said magnet to unlatch the door, said opening in said housing face being flanged inwardly around said hooked end to prevent access to the inside of the housing when said door is open; and means including a magnetizable member pivotally mounted in said housing and biased to position to cooperate with said latch arm to hold the latch in unlatched position, said magnetizable member being attracted by said magnet as the door is closed to free the latch for movement to latching position.

8. Interlock mechanism for an elevator hatchway sliding door comprising; a non-magnetic plate secured to the edge of the door and covering an opening in the edge of the door, said plate having a recess therein; a housing opposite said plate and extending into the door casing through an opening therein, said housing having a non-magnetic face with an opening therein opposite said recess and being secured to the door casing; a latch comprising a latch arm pivotally mounted in said housing and a catch having an arm extending through said opening in said housing face with an upwardly extending hooked end for entering said recess to latch said door, said catch being pivotally mounted in said housing in position to be operated by said arm into latching position, and shutting off said opening in the housing; a permanent magnet inside the door mounted on the rear of said plate; an armature carried by said latch arm in position to be attracted by said magnet as the door is closed to pull the latch arm into position to move said catch into position with its hooked end in latching position in said recess, thus latching the door

in closed position; a locking member pivotally mounted in said housing in back of said latch arm and having a key for engaging the back of said latch arm to lock the latch in latching position, said locking member being biased to locking position, said back of said latch arm having a recess opposite said key; an operating arm for said locking member outside the housing; and a retiring cam carried by the car for operating said operating arm to move said locking member into position with said key in position with respect to said recess in said latch arm to free the latch arm for backward movement, thereby unlocking said latch, the surface of said hooked end toward the housing being bevelled for cooperating with the upper edge of said recess in said plate upon the door being moved toward open position when said locking member is in unlocking position to force said latch backward into unlatching position against the force of said magnet to unlatch the door.

9. Interlock mechanism for an elevator hatchway door comprising; a keeper on the door; a housing secured to the door casing opposite said keeper; a latch mounted in said housing, said housing having an opening therein through which the latch extends to enter said recess, access to said housing through said opening being shut off by said latch; a magnet carried by the door for operating said latch; and contacts inside said housing controlled by said latch.

10. Interlock mechanism for an elevator hatchway door comprising; a keeper on the door having a recess therein; a housing secured to the door casing opposite said keeper, said housing having an opening therein opposite said recess; a movable latch mounted in said housing for entering said recess from said opening in said housing, said latch shutting off access to said housing through said opening; a permanent magnet carried by the door for pulling said latch as the door is closed into position in said recess to latch the door in closed position; means in said housing for locking said latch in latching position; contacts inside said housing closed by said latch when said door is latched; and additional contacts inside said housing closed by said locking means when said latch is locked.

11. Interlock mechanism for an elevator hatchway door comprising; a plate on the edge of the door having a recess therein; a housing opposite said plate and secured to the door casing, said housing having an opening in the face thereof opposite said recess; a latch having an arm pivotally mounted in said housing and a hook for entering said recess from said opening, said hook shutting off access to said housing through said opening; a permanent magnet inside the door mounted on said plate; an armature carried by said latch arm in position to be attracted by said magnet as the door is closed to pull the latch arm into position to move the hook into said recess and latch the door in closed position; a member in said housing operable to lock said latch in latching position; contacts inside said housing closed by said latch after said door is latched; and additional contacts inside said housing closed by said lock member after said latch is locked.

12. Interlock mechanism for an elevator hatchway door comprising; a non-magnetic plate secured to the edge of the door and covering an

opening in the edge of the door, said plate having a recess therein; a housing opposite said plate and extending into the door casing through an opening therein, said housing having a non-magnetic face with an opening therein opposite said recess and being secured to the door casing; a latch having an arm pivotally mounted in said housing and a hook for entering said recess from said opening in said housing face, said hook shutting off access to said housing through said opening in the housing face; a permanent magnet inside the door mounted on the rear of said plate; an armature carried by said latch arm in position to be attracted by said magnet as the door is closed to pull the latch arm into position to move the hook into said recess and latch the door in closed position; a locking member pivotally mounted in said housing for locking said latch in latching position; auxiliary door contacts inside said housing closed by said latch after said door is latched; and door lock contacts inside said housing closed by said locking member after said latch is locked.

13. Interlock mechanism for an elevator hatchway door comprising; a non-magnetic plate secured to the edge of the door and covering an opening in the edge of the door, said plate having a recess therein; a housing opposite said plate and extending into the door casing through an opening therein, said housing having a non-magnetic face with an opening therein opposite said recess and being secured to the door casing; a latch having an arm pivotally mounted in said housing and a hook for entering said recess from said opening in said housing face, said hook shutting off access to said housing through said opening in the housing face; a permanent magnet inside the door mounted on the rear of said plate; an armature carried by said latch arm in position to be attracted by said magnet as the door is closed to pull the latch arm into position to move the hook into said recess and latch the door in closed position; a locking member pivotally mounted in said housing in back of said latch arm and having a key for engaging the back of said latch arm to lock the latch in latching position, said locking member being biased to locking position, said back of said latch arm having a recess opposite said key; an operating arm for said locking member outside the housing; a retiring cam carried by the car for operating said operating arm to move said locking member into position with said key in position with respect to said recess in said latch arm to free the latch arm for backward movement, thereby unlocking said latch, the outer end of said hook having a bevelled surface for cooperating with an edge of said recess in said plate upon the door being moved toward open position when said locking member is in unlocking position to force said latch backward into unlatching position against the force of said magnet to unlatch the door; a pair of stationary contacts in said housing; contacting means carried by said latch arm for bridging said contacts after said door is latched; an additional pair of contacts in said housing; and contacting means carried by said locking member for bridging said additional contacts after said latch is locked.

ARTHUR ENNIS PRINCE.
